J. B. MASON, JR.
LEAD PENCIL.
APPLICATION FILED APR. 30, 1921.

1,411,117.

Patented Mar. 28, 1922

UNITED STATES PATENT OFFICE.

JAMES BRUCE MASON, JR., OF NASHVILLE, TENNESSEE.

LEAD PENCIL.

1,411,117.

Specification of Letters Patent. Patented Mar. 28, 1922.

Application filed April 30, 1921. Serial No. 465,660.

To all whom it may concern:

Be it known that I, JAMES BRUCE MASON, Jr., a citizen of the United States, residing at Nashville, in the county of Davidson and

5 State of Tennessee, have invented certain new and useful Improvements in Lead Pencils, of which the following is a specification.

This invention relates to lead pencils of the kind in which the lead is contained within 10 a casing and is propelled or fed when required through a suitable guide and through a pointed end or nozzle in such manner that the outer end of the lead may project only a short distance beyond the tip of the nozzle so that while sufficiently exposed for 15 writing purposes, it is not apt to break. Pencils of this general class have heretofore been provided with a magazine in which spare leads are stored in order that when 20 one lead has been worn out or nearly worn out, another may automatically be brought into working position. In this class of pencils the lead in use has generally been propelled by a pusher rod fed forward by a 25 screw threaded connection between the rod and the barrel or a tube within the barrel, and the construction has generally been such that before a fresh lead could be brought into position for use, it has been necessary 30 to slowly retract the pusher rod. Generally, also, the leads are delivered from the magazine by a rotary movement given to the magazine by a spring.

The object of my present invention is to 35 simplify the construction of automatic or mechanical pencils, to render them more accurate in operation, and to provide means whereby the slow retractive movement of the pusher may be avoided.

40 In carrying out my invention, instead of providing a rotary magazine I hold it in a fixed position and I associate with the magazine a feeder held under spring tension to move the leads successively from the magazine into engagement with a pusher. While this arrangement of magazine and feeder is preferred and is claimed in other co-pending applications, the improvements herein 45 claimed may be used in connection with other forms of magazines and feeders. I have radically departed from the old way of propelling the lead from the tip of the pencil, and instead of propelling the lead by a pusher acting on the inner end of the lead, I provide devices which grasp the lead 50 while in working position, feed it forward to a limited extent, then retract, take a new hold on the lead, and again feed it forward. The manner in which this is done will be hereinafter explained. 60

In the accompanying drawings:

Figure 1 shows a longitudinal central section of a mechanical or automatic pencil embodying my improvements.

Figure 2 is a perspective view of part of 65 the mechanism.

Figures 3, 4, and 5 are views on enlarged scales and in section on the line 3—3, 4—4, and 5—5 of Figure 1.

Figure 6 is a section on the line 6—6 of 70 Figure 1 with the parts in a different position.

The barrel A of the pencil may be made of suitable metal or other material. It is provided with a point B, which is hollow 75 and is detachably connected with the barrel at b. Within the tube is secured at c a hollow plug C which has a central threaded opening which receives the threaded end d of a guide tube D slotted at its lower end 80 d² as indicated in Figure 1. This tube is formed with a kerf or slot d' at its inner end to receive a screw driver or similar tool by means of which it may be driven into the block C. By adjusting the tube it may be 85 made to grip the lead V more or less tightly. It will be observed that the lower end of the tube bears against the inner walls of the point. The opposite end of the barrel A carries a collar E formed with a shoulder e, on 90 which rests a cap F which is removable from the collar. The collar is free to turn on the barrel, but it is secured by a screw thread at g to a tube G which rotates in the barrel. The tube G contains within it a stick 95 of erasive rubber G' which is covered and protected by the cap F. By turning the collar E, the tube G may also be turned and this tube G has a slot and pin connection at e² with the barrel A so that the tube 100 may have a slight longitudinal and rotary movement in the barrel. The mechanism operated by the collar E and the tube G will be hereinafter described.

About midway between the ends of the 105 barrel is secured a partition L and below this partition is located the magazine for spare leads and the feeder for the leads.

The partition L is held firmly in the barrel A by a lug l on the barrel which engages a slot in the partition. 110

It will be observed that the upper end

of the tube G is slotted at g^5 so that the rubber F is held tightly when the collar is screwed home.

The magazine is formed in a tube Q and 5 in a space surrounding the tube. The tube Q has a central opening q in its middle portion of the shape shown in cross section in Figures 5 and 6, and this opening connects with a slot q' extending to the outside of the 10 tube and connects with the space between the tube and the barrel. A blade Q' is secured to the outside of the tube Q on one side of the slot q' . The tube Q extends into the block C and projects into a recess 15 therein and it is secured thereto so that the tube Q does not rotate and has no endwise movement. The upper portion of the tube extends through the partition L and this tube contains the propelling rods P, P' 20 which feed the lead in use step-by-step through the nozzle.

Associated with the tube Q is a lead feeder, comprising two rings r, r' connected by a rod S. The upper ring r is connected 25 by a coiled spring T with the partition L. The feeder is adapted to turn about the axis of the tube Q when the magazine is being filled and when a fresh lead is being moved into working position. This construction of 30 magazine and feeder is not claimed herein as it is claimed in my application for patent filed April 30, 1920 No. 465,659. The manner in which leads are supplied to the magazine is also more fully explained in said application and need not be here repeated. It 35 is sufficient to say that when the magazine is supplied with spare leads, as soon as a lead is worn out or nearly used up, a fresh lead is automatically brought into 40 working position. The magazine tube Q, it will be observed, extends to a considerable extent above the partition L. In that portion above the partition, it is formed with circular openings through which the 45 upper ends of the propelling rods P, P' extend. These portions of the rods which extend through the upper part N of the tubular member Q are circular in cross section. The lower parts of the rods P, P' are 50 segmental in cross section as shown in Figures 5 and 6 for a purpose hereinafter described. The upper portion N of the tube Q is surrounded by a sleeve W which is free to turn around the part N and to slide thereon. The sleeve W is formed with a flange 55 w at its upper end to which is secured a coiled spring Q², the opposite or lower end of which is secured at w' to the partition L. This spring may be compressed and contracted so as to allow the tube W to have a 60 longitudinal movement and also a rotary movement. The rods P, P' extend into a cylindrical block O which is secured to the tube G so that when the tube G is reciprocated, the rods will also be reciprocated or

moved back and forth longitudinally. The block O is connected by a screw y' with a disc Y which is mounted in the tube G. The screw y' turns in the disc Y when the block is turned. The upper portions of the rods P, P' extend through a device X so constructed as to rotate or turn one of the rods, namely, P' without turning the other. In other words the upper portion of the rod P' is secured to the device X while the 75 other rod P extends through a curved slot p in this device. The device X is formed with a lug x which enters a hole w² in an upwardly projecting arm w³ of the sleeve W and this arm w³ enters a slot g⁴ in the 80 tube G. The manner in which these parts are assembled is shown in Figure 2.

As before stated, the lower portions of the rods P, P' are not circular but are segmental in cross section, and the flat faces 85 of the rods face each other in the manner shown in Figures 5 and 6. The two rods are arranged on opposite sides of the central longitudinal axis of the pencil, for permitting leads to be fed toward the center, 90 but at the proper time the rod P' is so turned as to grasp a lead in the magazine and when the rods are reciprocated the lead thus grasped is fed forward (see Fig. 6).

The rods P, P' grasp the lead V when in 95 working position in the manner shown in Figures 1 and 5. When it is desired to feed the lead forward the collar E is pressed inwards and the rods P, P' while grasping the lead are moved toward the point of the 100 pencil and carry the lead with them. This movement of course is only a short one, being sufficient merely to project the lead to the desired extent from the point of the pencil. Before releasing the collar, it is 105 given a slight turn for the purpose of causing the rod P' to turn and assume the position shown in Figure 6, thus releasing the grip of the rods on the lead. Then the collar E is moved upwards or outwards without 110 moving the lead and the rods assume their original position. Then the collar E is given a slight turn in the opposite direction from its initial turn and the rods are made to grasp the lead in the manner shown in Fig. 115 5, being then in a position for the next adjustment which may be performed by pressing the collar inwards or downwards as before explained.

The movements given to the mechanism 120 are very short but accomplish the purposes of the invention.

The flange w of the sleeve W is formed with a recess y. This is for the purpose of permitting the sleeve to pass the lug l when 125 being inserted into the barrel. After the sleeve is thus inserted, the parts of the sleeve may be given a slight turn so that the slot y will be out of line with the lug l in the manner shown in Fig. 1. Then the 130

partition L which is connected by the spring Q² with the flange w of the sleeve may be locked to the barrel in the manner shown in Fig. 1. It will be observed that the rod P carries a collar p'. This collar is firmly attached to the rod and serves to hold the device X in proper relation with the block O.

It will thus be seen that a lead may be fed or propelled through the point of the pencil without employing screw threads and the movement for feeding the lead is only a slight one. The parts may be retracted to feeding position very quickly and with slight movement. When filling the magazine, it is not necessary to retract the pusher rods out of the magazine as heretofore because by turning one of these rods, a free opening is left for the entrance of the leads, as indicated in Fig. 6.

It will be understood that the magazine is filled in the manner shown in my other co-pending applications and therefore this feature of the pencil is not herein further illustrated or described. It may be said, however, that in order to fill the magazine, the point B is detached from the barrel and the leads are inserted one at a time between the lip Q' and the feeder bar S. The feeder bar S being under spring tension, yields and permits the leads to be inserted in this way. Thereafter the feeder bar presses all the leads toward the central part of the magazine.

I claim as my invention:

1. A self-propelling lead pencil comprising a lead guide, a magazine for spare leads, means for feeding leads successively into working position in the magazine, and means for pushing the lead through the guide comprising devices for grasping the lead, means for pushing the grasping devices toward the point of the pencil and away therefrom, and means for giving a turning movement to a part of the grasping devices for releasing said devices from the lead while the grasping devices are being retracted.

2. A self-propelling lead pencil comprising a guide for a lead, pusher rods which grasp the lead while in working position, means for moving the pusher rod towards and from the point of the pencil, and means for turning one of the rods to release the lead from the grasp of the rods when the rods are being retracted.

3. A self-propelling lead pencil comprising a lead guide, a magazine for spare leads, means for feeding leads successively into working position in the magazine, pusher

rods operating in the magazine having a short reciprocating movement therein and one of which has a turning movement, and means for giving a short reciprocating movement to the rods while still in the magazine and for giving to one of said rods a turning movement whereby a lead may be grasped between the two rods or released therefrom.

4. A self-propelling lead pencil comprising a barrel, a lead guide in the barrel, pusher rods adapted to grasp a lead between them and which have flat opposing faces for engaging the lead, means for giving to the rods a short reciprocating movement, and devices for giving a turning movement to one of the rods.

5. A self-propelling lead pencil comprising a barrel, a lead guide within the barrel, pusher rods adapted to grasp a lead between them, a tube provided with means for giving it a short reciprocating movement, and a turning movement, a rod operating device connected with the tube to both reciprocate and to turn therewith and which serves to give a turning movement to one of the pusher rods.

6. A self-propelling lead pencil comprising a barrel, a lead guide within the barrel, a tube within the barrel, means for giving to the tube a short reciprocating movement and a short turning movement, pusher rods for grasping the lead between them, a sleeve surrounding the rods which is spring-supported and which is adapted to move longitudinally in the barrel, and also to turn therein, a pusher rod operating device connected with the sleeve to follow its movements, and connections between the pusher rod operating device and the operating tube.

7. A self-propelling lead pencil comprising a barrel, a lead guide in the barrel, pusher rods adapted to grasp the lead between them, means for giving to the rods a short reciprocating movement, and devices for giving a turning movement to one of the rods.

8. A self-propelling lead pencil comprising a lead guide, pusher rods operating in the pencil having a short reciprocating movement therein and one of which has a turning movement, and means for giving a short reciprocating movement to the rods and for giving to one of said rods a turning movement whereby a lead may be grasped between the two rods or released therefrom.

In testimony whereof, I have hereunto subscribed my name.

JAMES BRUCE MASON, JR.
